(57) **CLAIM**

The ornamental design for a compression collar for coupling a tube to a tube fitting as shown and described.

DESCRIPTION

FIG. 1 is a perspective view of a compression collar for coupling a tube to a tube fitting;

FIG. 2 is a perspective view of the compression collar shown in FIG. 1 being coupled with a tube and tube fitting; and, FIG. 3 is a perspective view of the compression collar shown in FIG. 1 being coupled with a tube and tube fitting.

The broken lines showing a tube and tube fitting in FIGS. 2 and 3 depict the environment of a compression collar and form no part of the claimed design.
